(57) **CLAIM**

We claim the ornamental design for a multiple pressure sensing system for peritoneal dialysis, as described and shown.

DESCRIPTION

FIG. 1 is an isometric assembly view of the pressure monitoring system thereof.

FIG. 2 is an illustrative isometric assembly view of a dosed pressure monitoring system thereof.

FIG. 3 is an illustrative isometric view of an open pressure monitoring system thereof.

FIG. 4 is a rear isometric view of the pressure monitoring system thereof.

FIG. 5 is an illustrative isometric view of the disposable aligner cartridge with integrated pressure measuring modules thereof.

FIG. 6 is an isometric front view of a load-cell based pressure measuring module thereof.

FIG. 7 is an isometric rear view of a load-cell based pressure measuring module.

FIG. 8 is an isometric view of the swappable aligner cartridge with dosed pressure chambers.

FIG. 9 is an isometric view of the swappable aligner cartridge with open pressure chambers; and,

FIG. 10 is an isometric assembly view of the open swappable cartridge in the pressure monitoring system.

The broken line showing details in FIGS. 1, 3, 4 and 5 is included for the purpose of showing environmental portions of the design. No claim is made to the portions shown in broken line.

1 Claim, 10 Drawing Sheets
